SIMMERING SHUTTER FOR HIGH-PRESSURE METAL VAPOR LAMPS

John Bernard Score Smyth, London, England, assignor to The General Electric Company, Limited, London, England

Application August 7, 1948, Serial No. 43,049
In Great Britain August 11, 1947

8 Claims. (Cl. 240—11.4)

1

This invention relates to lanterns for lamps of the high pressure metal vapour type such, for example, as high pressure mercury vapour (HPMV) lamps and which are suitable for lighting studios and the like.

It is well known that when such lamps are switched off after they have been working some time must elapse before they can be made to relight unless relatively complicated means for restarting are provided. It has previously been proposed that lanterns for use with lamps of this type should be provided with movable members arranged to surround or enclose the lamp so that, when the lantern is extinguished after giving light, the current through the lamp may be reduced to a low value and the electric discharge on the lamp being maintained by the heat energy reflected from the said members. This arrangement is normally termed a simmering arrangement.

One object of the present invention is to provide a lantern having a simple simmering arrangement.

According to the present invention, a lantern, for a lamp of the high pressure metal vapour type, includes a simmering arrangement comprising two pairs of arcuate shutters arranged to enclose at least the bulb or the like of a lamp in the operating position, each pair of shutters being mounted for rotation about an axis disposed to one side of the lamp, the axes being parallel and the two shutters of each pair being arranged to rotate in opposite directions to open and close.

Preferably the axes of the two pairs of shutters are parallel to the axis of the lamp and all the shutters are arranged to be operated together by a common means.

One construction of a lantern in accordance with the invention and suitable for lighting cinema studios and the like will now be described by way of example with reference to the four figures of the accompanying drawings in which Figure 1 shows a diagrammatic section through the optical axis of the lantern, Figure 2 shows an enlarged sectional front elevation of the lamp carrier and simmering arrangements, Figure 3 shows a section at line III—III on Figure 2 and Figure 4 is a sectional front elevation showing part of the lamp carrier not shown in Figure 2. 50

2

Referring now to Figure 1 the lantern comprises a substantially cylindrical housing 1 for a 10 kilowatt high pressure mercury vapour lamp 2, the lamp 2 being mounted on a carrier 3 as hereinafter described. Also mounted on the carrier 3 on the side remote from the projection lens 4 is a spherical concave reflector 5. In order to spread or close the beam of light from the lantern the carrier 3 is mounted on rails 6 extending the length of the lantern and may be moved to or from the lens 4 by rotating a handle 7 at the back of the lantern, the handle 7 being connected to a screw-threaded shaft 8 which engages with a collar 36 on the carrier 3.

15 Electric supply terminals 9 and 10 are provided in the back of the lantern, the negative terminal 9 being connected to the carrier 3 by the flexible lead 11 and the positive terminal 10 connected through the hinged device 12.

20 Referring also to Figures 2 and 3, the lamp 2 is located between centres 13 and 14, the bottom centre 14 being fixed to the carrier and the top centre 13 being spring-loaded and positioned by the side pillars 34 and 35. The carrier 3 also 25 has mounted on it the simmering arrangement associated with the lamp 2. Thus two pairs of shafts 15 and 16, and 17 and 18 are provided on the carrier 3, the two shafts of each pair being co-axial with their axes parallel to the axis of 30 the lamp 2, the two pairs being symmetrically disposed one on either side of the lamp. Each shaft 15, 16, 17 and 18 carries an arcuate metal shutter 19, 20, 21 or 22 arranged so that when the shutters 19 to 22 are in their closed position, they just overlap one another and substantially enclose the bulb 23 of the lamp 2 in a cylindrical container. Each pair of co-axial shafts 15, 16 and 17, 18 is arranged to form, in effect, a hinge upon which the associated shutters can be turned as hereinafter described.

35 The co-axial shafts 15 and 16 are connected to bevel gears 24 and 25 respectively which gears engage on diametrically opposite sides of a bevel gear 26 carried on an associated shaft 27 lying parallel to the optical axis of the lantern. Thus by rotation of the associated shaft 27 the pair of shutters 19 and 20 carried by the pair of shafts 15 and 16 move in opposite directions and are made to open or close.

40 In like manner movement of the shutters 21

and 22 is controlled by the associated shaft 28. The two shafts 27 and 28 associated with each pair of co-axial shafts 15, 16 and 17 and 18 are mechanically linked by a transverse member 29 as shown in Figure 4 and each shaft 27 and 28 is spring-biased over a dead centre position. The shaft 28 is geared to a collar 30 which carries a double key 31 engaging with axial slots in a further shaft 32 lying parallel to the optical axis of the lantern the shaft 32 extending through the rear of the lantern housing 1 and being terminated by an operating knob or lever 33 (see Figure 1). The further shaft 32 is fixed axially relative to the lantern housing 1 and is slotted to permit the carrier 3 with the lamp 2 and simmering arrangement to move as hereinbefore described.

When the lantern is giving light, the shutters 19 to 22 open as shown in the positions 19' to 22' in Figure 3 so that there is a substantially free optical path between the spherical reflector 5, the lamp 2 and the projection lens 4 at the front of the lantern. The shutters 19 to 22 are so arranged that they rotate through approximately 90° between their closed and open positions. The gearing between the operating lever 33 and the shutters 19 to 22 are all of 1:1 ratio so that the shutters are opened or closed, and thus the light from the lantern controlled, by rotating the lever 33 through approximately 90°. As previously described the shutters 19 will open and close with a snap action owing to the shafts 27 and 28 being spring-biased over a dead centre position.

I claim:

1. A lantern including an electric discharge lamp of the high pressure metal vapour type and a simmering arrangement for said lamp comprising a pair of arcuate shutters, means pivotally supporting said shutters for rotation about a fixed axis disposed to one side of the lamp, a second pair of arcuate shutters, means pivotally supporting said second pair of shutters for rotation about a second fixed axis parallel to said first-mentioned axis, and means to pivot the two shutters of each pair in opposite directions about their pivot axes into extreme closed and open positions, the shutters in the closed position enclosing at least the part of the lamp in which the electric discharge occurs and in the open position exposing said part of the lamp.

2. A lantern including an electric discharge lamp of the high pressure metal vapour type and a simmering arrangement for said lamp comprising a pair of arcuate shutters, means pivotally supporting said shutters for rotation about a fixed axis disposed to one side of the lamp, a second pair of arcuate shutters, means pivotally supporting said second pair of shutters for rotation thereof about a second fixed axis on the other side of said lamp and parallel to and spaced from said first-mentioned axis, and means to pivot the two shutters of each pair in opposite directions about the pivot axes into a closed position in which the shutters co-operate together to surround at least the part of the lamp in which the electric discharge occurs and to reflect back into the lamp heat energy radiated therefrom and into an open position in which the shutters expose said part of the lamp.

3. A lantern including an electric discharge lamp of the high pressure metal vapour type and a simmering arrangement for said lamp comprising a pair of arcuate shutters, means pivotally supporting said shutters for rotation about a fixed axis disposed to one side of the lamp, a second

pair of arcuate shutters, means pivotally supporting said second pair of shutters for rotation thereof about a second fixed axis on the other side of the lamp and parallel to and spaced from said first-mentioned axis, and a snap action mechanism to pivot the two shutters of each pair in opposite directions about their axes with a snap action into extreme closed and open positions, the shutters in the closed position co-operating together to surround at least a part of the lamp in which the electric discharge occurs and to reflect back into the lamp heat energy radiated therefrom, and in the open position exposing said part of the lamp.

4. For use in a lantern for a lamp of the high pressure metal vapour type, a simmering mechanism comprising two pairs of arcuate shutters, means mounting one pair of said shutters for pivotal movement in opposite directions about a fixed axis disposed to one side of said lamp, means mounting the second pair of shutters for pivotal movement in opposite directions about a second fixed axis parallel to the first-mentioned axis, and actuating means for pivoting the two shutters of each pair in opposite directions about their pivot axes into closed and open positions, the shutters in the closed position enclosing at least the part of the lamp in which the electric discharge occurs and operating to reduce radiation of heat therefrom, and in the open position exposing said part of the lamp.

5. For use in a lantern for a lamp of the high pressure metal vapour type, a simmering mechanism comprising two pairs of arcuate shutters, means mounting one pair of said shutters for pivotal movement in opposite directions about a fixed axis disposed to one side of said lamp, means mounting the other pair of shutters for pivotal movement in opposite directions about a second fixed axis on the other side of said lamp and parallel to the first-mentioned axis and a mechanism for pivoting the two shutters of each pair in opposite directions about their axes into a closed position in which the shutters co-operate together to surround at least the part of the lamp in which the electric discharge occurs and to reflect back into the lamp heat energy radiated therefrom, and into an open position in which the shutters expose said part of the lamp.

6. For use in a lantern for a lamp of the high pressure metal vapour type, a simmering mechanism comprising two pairs of arcuate shutters, means mounting one pair of said shutters for pivotal movement in opposite directions about a fixed axis disposed to one side of said lamp, means mounting the other pair of shutters for pivotal movement in opposite directions about a second fixed axis on the other side of said lamp and parallel to the first-mentioned axis and a snap action mechanism for pivoting the two shutters of each pair in opposite directions about their axes and moving the same with a snap action into extreme closed and open positions, the shutters in the closed position co-operating together to surround at least the part of the lamp in which the electric discharge occurs and to reflect back into the lamp heat energy radiated therefrom and in the open position being disposed so that they expose said part of the lamp.

7. A lantern including an electric discharge lamp of the high pressure metal vapour type, a housing, means to support said lamp in said housing, said housing having an opening through which light from the lamp is adapted to be projected, a reflector, means to mount said reflector

in said housing on the side of said lamp opposite to the side nearest the opening, and a simmering mechanism for said lamp, said simmering mechanism being inside the housing and comprising two pairs of arcuate shutters, means mounting one pair of said shutters for pivotal movement in opposite directions about a fixed axis disposed to one side of a line running from the reflector to the opening through the lamp, means mounting the second pair of shutters for pivotal movement in opposite directions about a second fixed axis parallel to the first-mentioned axis and on the opposite side of said line, and actuating means for pivoting the two shutters of each pair in opposite directions about their pivot axes into closed and open positions, the shutters in the closed position enclosing at least the part of the lamp in which the electric discharge occurs and operating to reduce radiation of heat therefrom and in the open position exposing said part of the lamp between the reflector and the opening.

8. A lantern as set forth in claim 7 wherein the actuating means for pivoting the two pairs of shutters includes a snap action mechanism to move the shutters with a snap action into extreme closed and open positions.
